his Attorney

UNITED STATES PATENT OFFICE.

LEO F. ADT, OF TROY, NEW YORK.

EYEGLASSES.

SPECIFICATION forming part of Letters Patent No. 766,574, dated August 2, 1904.

Application filed August 29, 1903. Serial No. 171,279. (No model.)

To all whom it may concern:

Be it known that I, LEO F. ADT, of Troy, in the county of Rensselaer and State of New York, have invented certain new and useful 5 Improvements in Eyeglasses; and I do hereby declare the following to be a full, clear, and exact description of the same, reference being had to the accompanying drawings, forming a part of this specification, and to the reference-numerals marked thereon.

My present invention relates to improvements in eyeglasses, and more especially to the studs or connections for attaching the spring and guards to the lenses; and it has for 15 its object to produce a device of this character adapted to be used universally with both horizontally and vertically disposed springs and guard arms or shanks, enabling either horizontally or vertically disposed springs to 20 be employed with guards having either horizontally or vertically extending attaching arms or shanks without modification from the existing forms thereof.

To these and other ends my invention consists in certain features of novelty and advantage to be hereinafter more fully described, and pointed out in the claims hereunto annexed.

In the drawings, Figure 1 is a perspective 30 view of a portion of an eyeglass employing a stud embodying my invention. Figs. 2 and 3 are similar views of modified forms of my invention. Fig. 4 is a sectional view on the line 4-4, Fig. 1; and Fig. 5 is a similar view of a 35 slightly-modified form thereof.

The same numerals of reference designate similar parts in the several views.

In the several embodiments of my invention, 40 1 designates the shank of the stud or attaching device, to which is connected the usual clip carrying the shoes 2, 2, adapted to rest upon the edge of the lens, and the perforated ears 3, 3, embracing the sides of the lens and receiving the fastening-screw 4. However, 45 these parts may be varied or entirely different forms of lens-attaching devices may be employed, as may be desired. To the opposite or inner end of the stud-shank 1 is attached a box 5, and in the embodiment shown in Fig.

1 said box is slotted or apertured, as at 6, to 50 receive the shank 7 of a guard and is also provided with a relatively offset seat 8, disposed substantially at right angles to the seat 6 and adapted to receive the end 9 of a spring. However, it will be understood that said seats 55 may be employed to receive the arm of either the spring or guard and that they may extend either partially or entirely through said box, as shown in Figs. 4 and 5. In the roof or cover 10 of the box is provided a perforation 11, 60 registering with perforations in the spring and guard arms and the threaded aperture 12, through which are passed a screw 13, the aperture 11 in said roof being of such size as to admit the head 14 of the screw and allow it to 65 bear directly upon the arm of the spring or guard or, if preferred, may be of such a relative size that said screw-head will bear upon and compress the roof 10 against the spring or guard arm to firmly clamp and lock said 70 parts in their proper positions.

In Fig. 2 the slots 15 and 16 therein intersect and are of such dimensions as to admit the insertion of the guard and spring both in each slot, and in employing this form the 75 arms of the spring or guard may both be inserted in the same slot or may be arranged in different slots in any desired relation to one another.

The form shown in Fig. 3 employs a channel or open slot 17 and a pair of apertures 18 18, formed in the flanges 19 19 and so arranged that the arm of a guard or spring inserted therein will be disposed, preferably, at right angles to the channel or slot 17 or to 85 the lenses of the eyeglasses, the usual fastening-screw being employed for securing the parts.

In the various embodiments of my invention it will be seen that spacing posts or 90 abutments 20 20 are provided and so disposed that the lateral edges of the guard or spring arms will bear against them, and thus be confined from displacement, and as the tops of these posts are connected by the roof 10 or 95 by the tops of the flanges 19 19 in the form shown in Fig. 3 it will be obvious that a device of this character is provided possessing

the requisite strength and rigidity for firmly securing the spring and guards in their proper positions, and by employing such a device the same may be universally used with springs 5 and guards having either vertically or horizontally extending attaching portions.

Any suitable method of construction may be employed in producing devices of this character, the shank portion 1 being preferably 10 formed and soldered or otherwise secured to the clip portion 2 3 and the box 5, which may be formed in any suitable manner. It will be observed that the form illustrated in Fig. 3 may be readily produced from a common or 15 well-known form of stud having the vertically-disposed channel by forming apertures in the flanges thereof, preferably of such dimensions as to admit the attaching portions of both the spring and guards, thereby enabling 20 such a device to be employed with springs and guards having their attaching portions extending in the same or opposite directions or at right angles relatively to each other.

By forming the stud with the roof portion 25 10 to receive the pressure of the screw it will be observed that a relatively stationary bearing-surface is provided to transmit the pressure of said screw to both attaching portions, and as said screw-head bears upon a stationary 30 portion of the stud all possibility of its loosening through motion of said attaching portions is eliminated. Moreover, as the posts or abutments between said bearing portions engage the lateral edges of said attaching portions of the spring and guard relative motion 35 or displacement thereof is effectually resisted.

I claim as my invention—

1. In eyeglasses, a device of the character described, comprising a body portion adapted 40 to be attached to the lenses, and seats angularly arranged therein to receive the attaching portions of the spring and guards, projections being formed adjacent said seats and constituting abutments for the lateral edges of said 45 attaching portions, and portions rigidly connecting the outer ends of said projections or abutments, and a fastening-screw for clamping said spring and guard ends in said seats.

2. In eyeglasses, a stud comprising a body 50 portion provided with lens-attaching devices, and a box carried thereby having seats formed therein to receive the attaching portions of the spring and guards at angles relatively to each other, projections being formed adjacent 55 said seats to engage the lateral edges of said attaching portions, and connecting portions between said projections adapted to engage the flat surface of said attaching portions, and a fastening-screw passing through said box 60 and attaching portions and adapted to clamp the latter within said box.

3. A device of the character described, comprising a body portion having lens-attaching means formed thereon, and a portion aper-

tured to receive the attaching ends of the 65 spring and guards and having projections formed between said apertures to engage the edges of said attaching ends, and portions connecting the ends of said projections, and a fastening-screw for clamping said spring and 70 guard ends in position.

4. A device of the character described, comprising a body portion carrying lens-attaching devices, and a portion having seats formed therein and arranged to receive the attaching 75 portions of the spring and guards in angular relation to each other, and projections formed by the intersection of said seats and constituting abutments for the edges of said attaching portions, a roof portion connecting 80 the ends of said projections, and a fastening-screw entering said roof and attaching portions for securing the latter within said box.

5. A device of the character described, comprising a body portion carrying lens-attaching 85 devices, and a box formed thereon having seats formed therein and adapted to receive the spring and guard attaching portions at right angles to the plane of the lenses, projections constituting abutments for the edges 90 of said attaching portions, and connected at their ends by a roof portion, and a fastening device for securing said attaching portions.

6. A device of the character described, comprising a body portion carrying lens-attaching 95 devices, and a closed box having seats formed therein to receive the attaching ends of the spring and guards in angular relation, projections formed between said seats and constituting abutments for the lateral edges of 100 said attaching portions, a roof portion connecting the ends of said projections and adapted to bear against the flat surfaces of the attaching portions, and a fastening-screw passing through said box and attaching portions, 105 and having a portion adapted to bear upon said roof and clamp said attaching portions within said box.

7. A lens-post for eyeglasses having lens-attaching devices, and a box having angularly- 110 arranged seats for receiving the attaching portions of the spring and guard and provided with spacing posts or abutments, adjacent the seats, and a portion connecting the ends of said posts or abutments.

8. A lens-post for eyeglasses provided with lens-attaching devices, and a box apertured to form seats to receive the attaching portions of the spring and guard, the seats being so arranged as to provide posts or abutments at the 115 corners of the box, and a roof portion connecting the ends of said posts or abutments to reinforce them.

9. A lens-post for eyeglasses, provided with lens-attaching devices, and carrying a box having angularly-arranged seats formed therein to receive the attaching portions of the spring and guard and providing spacing posts or 120

abutments for the lateral edges of the attaching portions, and a reinforcing connection between the ends of said spacing-posts.

10. A lens-post for eyeglasses carrying lens-attaching devices, and having a box provided with apertures arranged in angular relation therein and forming seats to receive the attaching portions of the bridge and guard, spac-

ing-posts forming abutments for the lateral edges of the attaching portions, and a roof portion connecting said posts and adapted to lie adjacent the flat sides of the attaching portions.
